EMMIT G. LATTA, OF SYRACUSE, NEW YORK, ASSIGNOR OF ONE-HALF TO HARVEY A. MOYER, OF SYRACUSE, NEW YORK.

RIBBON MECHANISM FOR TYPE-WRITING MACHINES.

933,652.

Specification of Letters Patent. Patented Sept. 7, 1909.

Application filed May 1, 1907. Serial No. 371,315.

To all whom it may concern:

Be it known that I, EMMIT G. LATTA, a citizen of the United States, residing at Syracuse, in the county of Onondaga and State of New York, have invented a new and useful Improvement in Ribbon Mechanisms for Type-Writing Machines, of which the following is a specification.

This invention relates more particularly to ribbon operating mechanisms for front strike or visible writing typewriting machines of the sort in which the ribbon is vibrated to and from printing position in front of or opposite to the printing point on the platen, so as to expose the writing to view except when making the impressions. Many features of the invention are not, however, restricted in application to such a typewriting machine, but are applicable to other kinds of typewriters and other machines employing an ink ribbon.

The invention is directed to improvements in the mechanism for feeding the ribbon lengthwise; the mechanism for reversing the direction of feed of the ribbon; the ribbon spools; and the ribbon vibrating mechanism, and the primary objects of the invention are to provide simple and efficient means, operated by the carriage driving power, for winding the ribbon from one spool onto the other; to provide reliable means of simple construction for automatically and promptly reversing the ribbon feed when the ribbon is exhausted from either of the spools; to accomplish this reversal by power or motor driven means in which power is stored manually independently of the operation of the carriage or other parts of the machine, and which is set in action without strain upon the ribbon; to equip the machine for the use of a single ribbon, or a plurality of ribbons carrying inks of different colors or characteristics, and to provide simple means whereby one or the other of the different ribbons or different parts of a single ribbon can be placed in position for use by the simple movement of a shift key or device; to produce means for equalizing the tension of a plurality of ribbons wound on a single pair of spools; to produce a ribbon spool of inexpensive and desirable construction adapted for use with one or more ribbons, and which has a part constituting a portion of the feed reversing mechanism; to provide a desirable and easy moving ribbon-vibrating mechani-

ism having provision for retaining the ribbon or ribbons stationary out of printing position to adapt the machine for stencil cutting; and to improve ribbon mechanisms for typewriting machines or other machines employing a ribbon in the respects herein-after described and set forth in the claims.

In the accompanying drawings, consisting of five sheets: Figure 1 is a fragmentary central longitudinal sectional elevation of a front-strike typewriting machine provided with ribbon mechanism embodying the invention. Fig. 2 is a plan view, partly in section, in line 2—2, Fig. 1, of the ribbon feeding and reversing mechanisms. Fig. 3 is a fragmentary front sectional elevation of the ribbon reversing mechanism, a portion of the reversing mechanism being broken away to disclose the ribbon vibrator and guides which are shown in elevation. Fig. 4 is a front elevation of the ribbon vibrator and guides, showing a different position of the guides from that shown in Fig. 3. Figs. 5 and 6 are front elevations of the two ribbon guides detached. Fig. 7 is a rear elevation of the vibrator detached. Fig. 8 is a sectional elevation, on an enlarged scale, of the ribbon vibrator and guides. Fig. 9 is a cross section thereof, partly in plan, in line 9—9, Fig. 8. Fig. 10 is a plan view, partly in horizontal section, of the ribbon tensioning and feed reversing mechanism. Fig. 11 is a detail section, on an enlarged scale, in line 11—11, Fig. 10, of the reversing trip device. Fig. 12 is a fragmentary horizontal section, partly in plan, on an enlarged scale, of one of the ribbon spools and adjacent parts of the ribbon mechanism; showing the spool exhausted and the parts in position to reverse the feed. Fig. 13 is a detached perspective view of the bridge and attaching device for the ribbon spools. Fig. 14 is a plan view of one of the ribbon spools. Fig. 15 is a vertical section thereof. Fig. 16 is a sectional elevation of one of the ribbon spools and associated parts, in line 16—16, Fig. 10. Fig. 17 is a broken plan view, partly in horizontal section, of a reversing mechanism of modified construction. Fig. 18 is a sectional elevation thereof in line 18—18, Fig. 17, but showing a different position of the hand crank for winding the reversing spring. Fig. 19 is a similar sectional elevation of another construction for the ribbon feed reversing motor.

Like letters of reference refer to like parts in the several figures.

A represents the top plate of the frame of a typewriting machine, and a, Fig. 1, a cross bar thereof at the upper rear portion of the keyboard.

B represents the platen, C the carriage on which the platen is journaled, C' the frame or support having suitable tracks or ways on which the carriage travels horizontally, C² the usual carriage-driving spring drum or motor, D one of the type-bars which are pivotally supported on a segment or curved support d below the platen, and E one of the key levers for operating the type-bars to which the key levers may be connected by the known means shown or any other suitable operating connections. The type-bars are provided with upper and lower case type, 20 and the frame or support C' for the carriage is hinged at c to the upper rear portion of the main frame whereby it can be shifted vertically to place the platen in printing relation to one or the other set of types on 25 the type-bars. The shift frame C' is raised and lowered and held in either printing position by an eccentric f connected to the shift frame by a pitman f' and oscillated by a pinion f² meshing with a toothed segment f³ 30 which is rocked by an arm f⁴ and key lever f⁵. The parts described form no part of the present invention and are thus briefly described and shown simply to enable a better understanding of the ribbon mechanism to 35 be described.

G G' represent two ink ribbons which are connected at opposite ends to suitable spools which are operated to feed the ribbon lengthwise, and they pass centrally through suitable vibrating guides in front of or opposite to the printing point of the platen. The two ribbons, which may carry inks differing in color or other characteristics, are preferably wound simultaneously, or together, face to 40 face on a single pair of spools H H'. The ribbons are wound on the spools simultaneously in the same manner as if a single ribbon were used, and for the sake of simplicity the ribbon feeding and reversing mechanism will be described as though only one ribbon were used. Each spool is preferably made of two sheet metal end plates or pieces which are formed, as shown in Figs. 12-16, by stamping or pressing. Each end plate 45 has a flange or flat portion h, a cupped or depressed central portion h', and a hub portion h² which extends outwardly centrally within the depression. When the two end disks are placed together the cupped central 50 portions form the cylindrical body of the spool, and the hub portions h² a hollow hub. The circular body walls bounding the depressions constitute tracks for the feed reversing trip device, as will hereinafter appear. The two end plates are secured to

gether by a projecting thimble h³ on each plate which extends through a hole in the other plate and is expanded or turned over the edge of the hole by spinning, or otherwise, to permanently connect the plates. 70 The cylindrical wall of the body of the spool is provided with an opening h⁴ and the spool is provided between the flanges thereof with a hinged ribbon-attaching device h⁵ which is hinged at one end to the spool adjacent to one end of the opening h⁴ and is adapted to bridge said opening or form a portion of the cylindrical wall of the spool body, as shown in Fig. 10. The opening h⁴ at top and bottom extends out into the 80 flanges of the spool and the ends of these portions in the flanges slope or incline gradually, as shown in Figs. 12 and 14; for a reason which will appear later. The device h⁵, which will be termed a "bridge," is preferably formed of a piece of thin spring metal bent upon itself to provide inner and outer clamping jaws or members between which the ribbon is gripped and held. The inner jaw bears at its ends against the cylindrical body of the spool at opposite sides of the opening h⁴, and is preferably bent inwardly between its ends so that it will enter the opening h⁴ and its inner surface form a continuation of the inner surface of the circular body wall or track of the spool on 90 which the reversing trip device travels, as will be hereinafter described. The bridge is hinged to the spool by integral trunnions or projections h⁶ at opposite sides of the connected ends of the jaws, which trunnions bear in small holes h⁷ in the flanges of the spool. Each end plate of the spool is provided with two of these holes so that the disks are alike and can be made from a single set of dies, but only one hole in each disk is employed for hinging the bridge thereto. 100 The outer jaw of the bridge is provided with integral teeth or prongs h⁸ which project into holes h⁹ in the inner jaw. The jaws are forced apart, as shown in Fig. 13, to place the ribbon between them, and when the jaws are released they spring together so that the teeth h⁸ penetrate the ribbon and securely hold the same. The bridge will securely hold one or more ribbons. The ribbon is readily attached to the bridge by swinging it out to the position shown by dotted lines in Fig. 14 and placing a pencil or other slender implement between the hinged end of the bridge and body of the spool which enables the outer jaw to be sprung away from the inner jaw. The outer jaw is preferably longer than the inner jaw to facilitate opening it. When the ribbon is wound upon the spool the second and subsequent turns of the ribbon pass outside of the bridge and hold the same closed against the body of the spool, and the outer jaw of the bridge being longer than the inner one a greater 110 120 125 130

leverage is secured whereby the ribbon will the more firmly hold the bridge closed. The spool is preferably provided with circular finger seats h^{10} in its flanges. The spool can be readily turned by hand to wind the ribbon thereon when this is desired, by placing a finger in the seat in its upper end.

The ribbon spools are mounted on upright spool shafts I journaled in suitable bearings 10 at opposite sides of the front portion of the top plate and are held on the shafts by releasable or friction connecting devices preferably consisting of spiral springs i which surround the shafts within the hollow hubs 15 of the spools. The inner end of each spring rests in one of two or more notches i' , Figs. 12 and 16, in the shaft, and its outer portion bears frictionally against the wall of the hollow hub with sufficient force to cause the 20 spool to turn with the shaft. If unusual strain is placed upon the ribbon, however, the spool can slip on the spring or the inner end of the spring can slip out of the retaining notch in the shaft to thereby allow the 25 spool to turn on the shaft and prevent injury to the ribbon. This spring also serves to retain the spool on the shaft in the ordinary usage or handling of the machine, but allows the spool to be slipped off of the shaft when 30 force enough is applied to cause the spring to disengage the notch in the shaft. The spring i and the bridge h^5 are placed in position in the spool before the end disks are secured together and no additional securing 35 means for the spring or bridge are required. The complete spool is thus composed of few parts which can be cheaply made and assembled. The spools are light and strong and are reversible and interchangeable on the shafts, 40 which enables both sides of the ribbon to be used, and there are no detached parts which can be lost or mislaid. The spool bodies and flanges are of larger diameter than usual, to increase the spool capacity for a plurality of 45 ribbons and cause less difference in the feed of the ribbons when the spools are nearly full and nearly empty. Spools constructed as described, with the means for attaching them to their shafts and attaching the ribbon 50 thereto, would be desirable in many forms of typewriting and other machines having ribbon-operating mechanisms of different constructions.

The ribbon feed mechanism is preferably 55 constructed as follows, see especially Figs. 1, 2 and 16: K K' represent two bent or bell-crank levers which are arranged horizontally beneath the top plate A and are fulcrumed between their ends near the rear of 60 the machine on pivot pins k depending from the top plate, or in any other suitable manner. The levers have arms which extend toward each other from their fulcras and are connected, for instance, by a pin k' , Fig. 2, 65 on one lever entering a slot k^2 in the end of

the other lever. k^3 represents a screw or threaded part secured or connected to the carriage-driving spring barrel or motor so as to be driven thereby. One of the feed levers is provided with a stud or pin k^4 which 70 engages the threads of this screw, so that the rotation of the screw rocks the two feed levers on their fulcras. When the spring barrel turns slowly in one direction in moving the carriage to the left, the feed levers 75 are slowly rocked in one direction, and when the carriage is set back and the rotation of the spring barrel reversed, the feed levers are rocked in the opposite direction, the levers being moved whenever the barrel turns. The 80 feed levers have forwardly projecting arms provided at their front ends with toothed segments or racks k^5 which mesh with toothed pinions k^6 mounted to turn freely on the lower ends of the spool shafts I . Ratchet 85 wheels L are fixed to the spool shafts, preferably above the pinions k^6 , and pawls l carried by arms l' projecting from the pinions k^6 cooperate with these ratchet wheels to turn the spool shafts. The noses of the pawls 90 l are pressed toward the ratchet wheels by hidden springs in the pawls. l^2 represents holding dogs which are pressed toward the ratchet wheels by hidden springs to engage the teeth thereof and hold the wheels from 95 rearward rotation. The feed pawls oscillate back and forth with the feed levers, which swing together in opposite directions, and one of the pawls is held by its spring against its ratchet wheel to turn the same and the connected spool shaft and spool, but the other pawl is held out of engagement with its ratchet wheel by one of two reversing levers 100 M M' , Figs. 2 and 16. One of these levers is arranged horizontally above each ratchet 105 wheel, being pivoted at its rear end on a screw m secured to the frame top or in any other suitable manner. The reversing levers have loops between their ends surrounding the spool shafts, each loop having at one side 110 a segmental circular inner edge which in one position of the lever is concentric with the spool shaft, see the lever M at the left in Fig. 2. In the position of the reversing levers shown in Fig. 2, the circular edge of the lever M at the left engages an upright stud or projection m' on the tail of the adjacent feed pawl and holds the pawl out of engagement 115 with its ratchet wheel, and the other side of the loop of this lever bears against the end of the adjacent holding dog l^2 and also holds this out of engagement with the ratchet wheel, while the reversing lever M' at the right in Fig. 2 is held out of engagement 120 with the adjacent feed pawl which can therefore engage its ratchet wheel as the pawl is moved back and forth. The holding dog is also allowed to engage this ratchet wheel. In this position of the reversing levers, therefore, the right hand ratchet wheel and con- 125 130

nected spool are turned to wind the ribbon thereon and the other ratchet wheel and connected spool are released so that the spool can turn freely as the ribbon is unwound therefrom.

To reverse the direction of feed of the ribbon the reversing levers are shifted to the position indicated by dotted lines in Fig. 2, when the feed pawl for the right-hand ratchet wheel will be rendered inactive and that for the left-hand wheel will come into action. The reversing mechanism for thus shifting the reversing levers is preferably constructed as follows, see especially Figs. 2, 10 and 11. N represents a horizontal reversing shaft which is journaled transversely of the machine beneath the front portion of the top plate A in suitable bearings n depending from the top plate. This shaft is provided with cams n' n² having grooves in which engage studs or pins n³ on the front ends of the reversing levers. The cam grooves are so shaped that when the shaft is turned a half revolution the reversing levers will be shifted and the direction of feed of the ribbon reversed. The reversing levers are held stationary in either position by the cams n' n². The reversing shaft is preferably turned in one direction to automatically reverse the ribbon feed, by a suitable driving spring or motor which is wound by hand to store power therein. In the construction shown in Figs. 1 to 3, 10, and 11, a spring n⁴ is coiled about the reversing shaft, being attached at one end to the shaft by a pin n⁵, Figs. 2 and 10, or other means, and at its other end to a pin n⁶ depending from the top plate, or other stationary part of the machine. A hand crank n⁷ is provided at one end of the shaft for turning the same to wind the spring. This crank, see Fig. 3, is loose and adapted to slide on the shaft to engage a pin n⁸ on the shaft in a notch in the hub of the crank, whereby the shaft can be turned by the crank. Normally, however, the crank is held out of engagement with the pin by a spring n⁹ surrounding the shaft within the hub of the crank between shoulders on the hub and on the shaft. The crank is thus permitted to hang stationary while the shaft is turned by its spring n⁴.

O O' Figs. 10, 12 and 16, represent two trip levers or devices which are fulcrumed between their ends within the spool pockets in the top plate below the ribbon spools. The inner or rear ends of the trip lever have upright studs or parts which extend up into the lower depressions of the spools and bear against the inner surface of the surrounding circular walls or tracks of the spools, see Figs. 10 and 16. The outer ends of the trip levers extend through holes in the spool pockets toward the reversing shaft N, adjacent to pins or projections p p'

which, in the construction shown, secure the cams on the shaft and extend from opposite sides of the shaft. The outer ends of the trip levers are normally held in the paths of the pins p p' and the studs at their inner end against the circular walls or tracks of the spools by suitable light springs p², Fig. 10, connecting the trip levers to adjacent parts of the top plate. One of the pins p p' normally rests against the underside of the adjacent trip lever, as shown at the left in Fig. 10 and in Fig. 11, and holds the shaft from being turned by its spring n⁴. The shaft is thus held stationary so long as the ribbon wound on the spools holds the bridges h⁵ before mentioned, closed, to form a continuous track for the studs at the inner ends of the trip levers. When, however, the ribbon is unwound from either spool it will allow the bridge thereof to swing outwardly away from the body of the spool, as shown in Fig. 12, so that when the opening h⁴ in the body of the spool arrives opposite to the stud on the trip lever the stud can enter the opening, thereby permitting the outer end of the trip lever to be pulled by its spring p² out of engagement with the pin on the reversing shaft. This releases the shaft and it is turned a half revolution by its spring, or until arrested by the engagement of the other pin against the underside of the other trip lever. This half revolution of the shaft acting through the cams shifts the reversing levers M M' to stop the winding of the full spool and cause the empty spool to commence winding the ribbon thereon. This action of the reversing mechanism is immediate and no strain whatever on the ribbon is required to operate the trip levers and start the reversing action. The reverse takes place without strain on the carriage-driving spring or printing mechanism, and moreover, the reverse can only be effected automatically when the ribbon is practically all exhausted from one of the spools. As soon as the reversing shaft has been tripped the then empty spool begins at once to rewind the ribbon thereon, and, as at this time the detent for this spool is free from the pin on the reversing shaft, and its movement is only resisted by the light spring p², the trip lever will be forced back to the normal position by the engagement of the inclined end of the hole h⁴ in the bottom flange of the spool with the stud of the trip lever. The continued winding of the spool swings the bridge back to closed position, where it will be held by the first coil of the ribbon against the opposing pressure of the spring p² acting through the trip lever. The relatively greater length of the bridge than the hole h⁴ in the spool gives the ribbon sufficient leverage to hold the bridge closed against the pressure of the trip lever with only a single turn of the

ribbon about the spool. The outer ends of the trip levers preferably have inclined under faces p^3 , Fig. 11, so that the pressure of the pin on the reversing shaft against this face assists the trip lever spring in moving the trip lever. The inclination of the face p^3 is slight and the trip lever for the full spool will not be swung by the engagement of the pin off the reversing shaft therewith in the event that the shaft is turned at a time when the stud of the trip lever bears against the bridge b^5 , as the bridge will be firmly held closed by the numerous turns of the ribbon surrounding it. The outer ends of the trip levers also have relatively steep-inclined upper faces p^4 , Fig. 11. When the reversing shaft is turned by hand in the opposite direction to wind its driving spring the pins on the shaft alternately engage these upper inclined faces p^4 of the trip levers and swing the levers out of the paths of the pins. The reversing spring should be wound up when a new ribbon is applied to the machine and it will reverse the feed a sufficient number of times to exhaust the ink from one side of the ribbon. Then the ribbon can be reversed and the other side used by interchanging and inverting the spools and again winding the reversing spring. However, the spring can be wound up whenever necessary or desired. As the cams turn with the shaft in winding the spring, the reversing levers are oscillated back and forth and it will thus be seen that the feed of the ribbon can be reversed at any time by turning the reversing shaft by hand in the direction to wind the driving spring. The shaft without the spring could, if desired, be employed for manually reversing the ribbon feed.

The construction of the reversing mechanism could be changed in various respects without departing from the principle thereof.

In the construction shown in Figs. 17 and 18, one end of the driving spring (not shown) for the reversing shaft N' is attached to the shaft as before, and the other end of the spring is attached to the hub of a pinion p^5 which is loose on the reversing shaft. This pinion meshes with another pinion p^6 on a winding shaft p^7 which is journaled in suitable bearings depending from the top plate A and is provided with a crank p^8 for turning it. The crank is connected to the shaft so that it can slide longitudinally thereon, for instance, by a screw p^9 entering a key way in the shaft. When the crank is pulled out to the position shown in Fig. 18 it can be turned to rotate the winding shaft and wind the spring, but when the crank is shoved in to the position shown in Fig. 17, it will be held by the winding spring against the flange of the top plate and hold the winding shaft and reversing shaft from rotation

by the spring. In this construction the rotation of the reversing shaft by its spring shifts the reversing levers and reverses the direction of feed of the ribbon, but the reversing shaft remains stationary and does not move the reversing levers when the winding shaft is turned to wind the spring. In this construction the trip lever O' shown is provided with an anti-friction roller to bear on the circular track of the spool. This construction of the reversing mechanism is somewhat more expensive to build than the other but it works very easily and is more sensitive in action, and as the reversing levers are not moved in winding the driving spring it is not necessary for the operator to observe the direction in which the ribbon is feeding before winding the spring in order to have the ribbon feed in the same direction when the spring is wound before the ribbon is exhausted from one of the spools.

Fig. 19 shows still another construction of the reversing mechanism in which p^0 represents a winding shaft journaled in a suitable bearing on the frame and geared to the reversing shaft by a wheel p^{10} loose on the winding shaft and a pinion p^{11} secured to or formed on the adjacent cam on the reversing shaft N^2 . The winding shaft is provided with a fixed key or thumb piece for turning it, and a spiral driving spring p^{12} is secured at its inner end to the inner end of the winding shaft and at its outer end to the loose gear wheel p^{10} . The winding shaft is held from backward rotation by a spring detent p^{13} secured to the bearing bracket for the shaft with its free end engaging ratchet teeth p^{14} on the hub of the thumb piece. In this construction also the reversing shaft is not turned backwardly in winding the driving spring. The spiral spring acts to reverse the ribbon feed the same as the coil spring around the reversing shaft. The chief advantage of this construction lies in the fact that one revolution of the winding shaft will store power to revolve the reversing shaft a number of times. The ribbon guiding and vibrating mechanism is preferably constructed as follows: The ribbons pass from the spools through stationary guides q , Figs. 1, 3 and 10, located adjacent to the spools and having separate slots for each ribbon to hold the ribbons out of contact at these points, and from these guides the ribbons extend rearwardly and through vibrating guides Q Q' , Figs. 1-6, 8 and 9, which are located in front of and normally below the printing point and are supported and vibrated together by a vibrator or carrier R. The guides are arranged one directly in rear of the other to move or shift vertically in ways r at the opposite edges of the rear side of the vibrator, and have forked upper ends with side guide loops for the ribbons. The guides are pref-

erably made of spring metal and flexed slightly to insure the necessary friction for holding them stationary in the ways of the vibrator except when purposely shifted. The 5 guides are held in the vibrator one higher than the other to hold the upper portion of one ribbon above the upper edge of the other ribbon where it can be engaged by the type to make the impressions, and the guides 10 can be shifted on the vibrator to thus hold whichever ribbon is to be used higher. The vibrator, which is arranged in front of the scale bar of the carriage, is provided with a hole r' through which, and similar holes r^2 in 15 the guides, the scale can be seen. Each guide has pointers or indexes r^3 at the upper and lower ends of its hole r^2 , and in one position of the guides the upper pointer of one guide and the lower pointer of the other will be exposed 20 through the hole in the vibrator, see Fig. 3, to indicate the printing point on the scale. When the guides are shifted the upper pointer of the other guide and the lower pointer of the first guide will be likewise 25 exposed through the hole in the vibrator.

The vibrator or carrier R, Figs. 1-3 and 7-9, is arranged in upright position below and in front of the printing point of the 30 platen. The upper end of the vibrator, like the guides, is forked for the passage of the type in moving to the platen, and its lower end is also slotted or forked. The vibrator is movably supported in upright position by 35 upper and lower parallel links r^4 r^5 each pivoted in a slotted front extension r^6 of the carriage shift frame and having forwardly-extending separated arms pivoted to the opposite sides of the vibrator. The upper link 40 r^4 has a rearwardly projecting arm connected by a link r^7 to a central rock arm r^8 secured to a horizontal rock shaft r^9 which is journaled at opposite ends in suitable bearings at the sides of the machine. The rock 45 shaft is provided with forwardly extending side arms r^{10} from the front ends of which is suspended a universal bar or bail S which extends horizontally across the machine just below the key levers so as to be engaged and 50 operated to raise the vibrator whenever a key lever is depressed to operate a type-bar. The vibrator is returned to its normal lowered position and the universal bar held up in its normal position by a suitable spring, 55 such as s, connecting the rock arm r^8 to the top plate. The key levers are provided adjacent to the universal bar S with notches s' in their lower edges. The universal bar can be swung forwardly on the pivotal connections with its supporting arms to place it beneath these notches s' , and when so placed the universal bar will not be depressed when the key levers are operated, and the vibrator 60 will remain stationary in its lower position

and hold the ribbons down below the printing point, thus adapting the machine for stencil cutting. The universal bar is held in the forward position when placed in this position, by any suitable means such, for instance, as a detent, not shown.

If desired, the ribbons can be prevented from feeding lengthwise while stencil cutting, by raising the spool that is winding the ribbon on its shaft until its spring i rests on top of the shaft which will allow the spool to remain stationary. The vibrator being mounted on the swinging parallel links is always held upright and moves with much less friction than a vibrator sliding in guides, for the forward pull of the ribbons causes cross strains in the guides of a sliding vibrator. This saving in friction fully equals the extra work of vibrating the second ribbon. The link r^7 connecting the rock arm r^8 to the rearwardly projecting arm of the vibrator links allows the vibrator to move up and down with the carriage shift frame when shifted and produces a nearly like movement of the vibrator in both positions of the shift frame.

The guides are shifted to change the ribbons by the following mechanism: T, Figs. 4, 8 and 9 represents a rocker or lever pivoted centrally on the vibrator by a screw t and having slots in its ends in which engage pins t' t^2 , one projecting from one side of one guide Q and the other from the opposite side of the other guide Q. The guides and vibrator are slotted or forked at their lower ends, as shown, to allow the pins on the guides to project forwardly into the slots of the rocker T. t^3 represents an operating lever for the guides. This lever, see Figs. 1 and 2, is pivoted at its rear end in any suitable manner to the forked extension 105 of the shift frame, and its front end extends forwardly between the legs of the vibrator and guides beneath a V-shaped central part or projection on the rocker T. The lever t^3 is jointed between its ends at t^4 or is otherwise constructed or mounted so that its front ends can swing horizontally as well as vertically. The lever t^3 is connected by a rod t^5 to a ribbon shift lever or key U which is arranged centrally of the machine at the upper portion of the keyboard, being preferably pivoted centrally to a bracket u secured on the cross bar a of the frame. The front end of the key lever is normally held up and the operating lever t^3 held down by a suitable 110 spring, such as that shown at u', Fig. 1, connecting an arm on the shift key with its supporting bracket. The front end of the guide-operating lever t^3 is normally held centrally with regard to the rocker T by an upright spring guide V secured centrally to the type-bar segment and having a loop at its upper end through which the shift rod t^5 115

passes and is guided. When the shift key U is depressed and the lever t^3 raised, it will engage one or the other inclined edge of the V-shaped portion of the rocker T , depending upon the position of the rocker, and will be thereby deflected to one side or the other and raise the lower arm of the rocker no matter which end of the rocker is the lower, and the rocker swinging on its pivot will elevate the lower guide and lower the upper guide to change the ribbons. The spring guide will yield laterally to allow the side-wise deflection of the operating lever t^3 , and when the shift key is released and the operating lever lowered, the front end of the latter will be returned to the normal central position beneath the rocker T by the spring guide V . The rear end of the operating lever t^3 being pivoted to the carriage shift frame rises and falls with the same, but the front end of the lever being connected to the shift rod t^5 has but slight movement at such times, the arrangement being such that the lever will operate similarly upon the rocker T in either position of the shift frame and carriage, it only being necessary to depress the shift key U farther when the carriage is in its upper position. The construction permits an instant change of ribbons by the simple depression of a key or lever most favorably located in the keyboard, and like movements of the same part always change the ribbon no matter which one is in position for use, thereby avoiding confusion and mistakes, as well as saving time. The front guide Q is preferably provided with a second operating pin t^6 below its other one t^5 to enable a single ribbon to have two fields of different kinds of ink to be used if desired. In such case the rear ribbon is removed and the pivot screw t for the rocker is loosened so that the rocker can be engaged with the lower pin t^6 . Then when the guide is in its lower position it will hold the upper field of the ribbon in position to vibrate to and from printing position, and when the guide is raised by depressing the shift key it will place the lower field of the ribbon in position to vibrate to and from printing position. The shifting means act to shift a single ribbon in the same manner as when two ribbons are used but shift it from a higher position so that the printing cannot be seen when the lower field is being used. This, however, is not a serious objection as the lower field is used but little. By this arrangement either one or two ribbons can be used in the machine without adding any part to or removing any part from the machine, and in either case printing can be done with different inks. The ribbon vibrating and shifting mechanism described could also be used with ribbons wound on separate pairs of spools suitably arranged

and operated. The guide for the second ribbon could, if preferred, be omitted on machines designed for use with only one ribbon. The guides could also be arranged to support one ribbon its full width above the other, but it is preferred to have the ribbon overlap, as shown.

In using two ribbons on the same pair of spools it is found a little difficult to maintain both ribbons at the same tension, and also that the ribbon that is used the most seems to stretch to an objectionable degree. To obviate this a tension device W , Figs. 10 and 12, is provided near the fixed guide at each spool, preferably consisting of an arm pivoted to a lug on the top plate and having an upright pin in its free end, which stands beside the ribbons and has its lower end connected to a spring w , the other end of which is connected to a lug on the underside of the fixed ribbon guide at a point in rear of the pivot for the tension arm. By this arrangement of the spring the tension arm is drawn in either direction from its central position, and if the ribbons be properly applied the arm is permitted to remain out of the way, as at the right in Fig. 10, but if the ribbons are not about equally tensioned the pin on the arm is placed against the loose ribbon, as shown at the left in Fig. 10, so that the spring w acts to take up the slack in the ribbon. As shown, the rear ribbon is the one acted on by the tensioning device, but it may be set the other way and act on the front ribbon in the same way.

I claim as my invention:

1. In a typewriting machine, the combination of a pair of ribbon spools, a carriage-driving motor, a pair of bell-crank levers mounted to swing substantially horizontally, and operative connections between said levers and said carriage-driving motor and between said levers and the spools for rotating the spools to wind the ribbon thereon, substantially as set forth.
2. In a typewriting machine, a pair of ribbon spools, a carriage-driving motor, a pair of connected bell-crank levers arranged at opposite sides of the machine to swing together substantially horizontally, operative connections between one of said levers and said carriage-driving motor, and operative connections between each of said levers and one of the spools for rotating said spool, substantially as set forth.
3. In a typewriting machine, the combination of a pair of ribbon spools, a pair of pivotally connected bell-crank levers, means for swinging said levers simultaneously in opposite directions, and connections between said levers and said spools for turning one of the spools, substantially as set forth.
4. In a typewriting machine, the combination of a pair of ribbon spools, a pair of

- levers pivoted at opposite sides of the machine to swing horizontally and having arms projecting toward the center of the machine and connected to each other, means for oscillating said levers, and means for operatively connecting either of said levers to its spools for rotating the spool and disconnecting the other lever from its spool, substantially as set forth.
10. 5. In a typewriting machine, the combination of a carriage driving motor, a pair of rotary spool shafts, gears loosely mounted on the shafts, a pair of pivoted levers having teeth meshing with said loose gears, constantly acting operative connections between said levers and said carriage driving motor, and means for operatively connecting the gear on either of said spool shafts to its shaft, substantially as set forth.
15. 6. In a typewriting machine, the combination of a carriage driving motor, a pair of pivoted levers, connections for moving said levers at all times with said motor, a pair of spool shafts, gears loose on said spool shafts, teeth on said levers meshing with said gears on the spool shafts, and means for alternately and simultaneously connecting one of said gears with its spool shaft and disconnecting the other gear from its spool shaft, substantially as set forth.
20. 7. In a typewriting machine, the combination of a carriage driving motor, a screw connected to rotate therewith, a pair of connected levers pivoted at opposite sides of the machine to swing horizontally and actuated by said screw, a ribbon spool adapted to be rotated by each of said levers, and means for operatively connecting either lever to its spool, substantially as set forth.
25. 8. In a typewriting machine, the combination of a pair of ribbon spools, power-driven means for driving said spools including a pair of levers whose pivotal axes are substantially parallel with the axes of said spools, a pair of reversing levers substantially parallel with said driving levers for connecting said spools with and disconnecting them from said driving means, and means for simultaneously swinging said reversing levers, substantially as set forth.
30. 9. In a typewriting machine, the combination of a carriage-driving motor, a pair of spools, means including horizontally-swinging levers for transmitting motion from the carriage-driving motor to said spools to rotate them, a pair of reversing levers, pivotally supported adjacent to said spools to swing horizontally for connecting and disconnecting said spools to and from said motor-driven levers, and means for swinging said reversing levers from one to the other of two positions and holding them against accidental movement, substantially as set forth.
35. 10. In a typewriting machine, the combination of a carriage-driving motor, a pair of spools, horizontally-swinging levers oscillated by said carriage-driving motor for driving said spools, ratchet and pawl connections between said levers and said spools, a pair of horizontally-swinging reversing levers having curved faces for holding said pawls out of engagement with said ratchets, and means for swinging one of said reversing levers into position to engage the pawl controlled thereby and the other lever into position to release the pawl controlled thereby, substantially as set forth.
40. 11. In a typewriting machine, a ribbon spool consisting of two end plates each having a central depressed part, the depressed parts being united to connect the end plates and form the body of the spool, substantially as set forth.
45. 12. In a typewriting machine, a ribbon spool consisting of two end plates each having an integral circular depressed part, the depressed parts being united to connect the end plates and form the body of the spool, and having the central portions of such depressed parts turned outwardly to form the hub of the spool, substantially as set forth.
50. 13. In a typewriting machine, a ribbon spool composed entirely of two plates having depressed central portions secured together face to face, each plate forming one end flange and one-half of the body of the spool, substantially as set forth.
55. 14. In a typewriting machine, a ribbon spool consisting of two end plates each having a depressed circular part forming one-half of the spool body, and each depressed part having an integral projection passing through a hole in the other depressed part and turned down thereon to secure the two plates together, substantially as set forth.
60. 15. In a typewriting machine, a ribbon spool shaft, a spool having a hollow hub forming an annular chamber around said shaft, and a part inclosed within said chamber in the hub outside of said shaft and forming a releasable connection for causing the spool to turn with the shaft, substantially as set forth.
65. 16. In a typewriting machine, a ribbon spool shaft, a spool having a hollow hub forming a chamber in the spool outside of said shaft, and a spring device located within said chamber and carried by the hub for releasably connecting the spool to the shaft to turn therewith, substantially as set forth.
70. 17. In a typewriting machine, a ribbon spool shaft, a spool, and a detached spring arranged within the spool hub outside of the shaft and having a snap engagement with the shaft and a frictional engagement with the hub, substantially as set forth.
75. 18. In a typewriting machine, a ribbon

- spool, and a ribbon attaching device mov- 65
ably mounted on the spool and comprising
a pair of spring-holding jaws for the ribbon
connected at one end and adapted to be
sprung apart at the other end to receive the
end of the ribbon, substantially as set forth.
19. In a typewriting machine, a ribbon
spool having ribbon holding jaws pivotally
connected at one end to the spool between
its flanges, and adapted to swing outwardly
on its pivot and have its jaws sprung open
to receive the ribbon, substantially as set
forth.
20. In a typewriting machine, a ribbon
spool having a ribbon attaching device pivot- 70
ally connected therewith, and provided with
holding jaws, one of which has projecting
points adapted to penetrate the ribbon, sub-
stantially as set forth.
20 21. In a typewriting machine, a ribbon
spool having a ribbon attaching device pivot- 75
ally connected thereto and having holding
jaws, the outer jaw being longer than the
inner jaw and forming a handle by which
the jaws may be sprung open to receive the
ribbon, substantially as set forth.
22. In a typewriting machine, the combi- 80
nation of a ribbon spool having a circular
track at one end, and ribbon feed reversing
mechanism including a trip device having
a part which travels against the inner sur-
face of said track, substantially as set forth.
23. In a typewriting machine, the combi- 85
nation of a ribbon spool having a circular
recess in one end, and ribbon feed reversing
mechanism including a trip device having a
part which is located in said recess and
travels on the circular wall thereof, substan-
tially as set forth.
40 24. In a typewriting machine, the combi- 90
nation of a ribbon spool having a recess in
one end forming a circular track, and ribbon
feed reversing mechanism including a trip
device having a part located in the recess
and bearing against said circular track, sub-
stantially as set forth.
25. In a typewriting machine, the combi- 95
nation of a ribbon spool having a recess in
one end with a circular wall, said circular
wall having an opening, and ribbon feed
reversing mechanism including a trip device
which travels on said circular wall and is
adapted to enter said opening when the rib-
bon is exhausted from the spool, substan-
tially as set forth.
26. In a typewriting machine, the combi- 100
nation of a ribbon spool having a circular
body wall with a circumferential opening
therein, and ribbon feed reversing mechan-
ism including a trip device normally bearing
on the inside of said body wall and adapted
to enter said opening and release the revers-
ing mechanism when the ribbon is exhausted
from the spool, substantially as set forth.
27. In a typewriting machine, the combi- 105
nation of a ribbon spool having a circular
wall with a circumferential opening therein,
a bridge normally closing said opening and
forming a part of said wall, and ribbon re-
versing mechanism including a movable trip
device which travels on the inside of said
wall and is adapted to enter said opening
to release the reversing mechanism when the
ribbon is exhausted from the spool, substan-
tially as set forth.
28. In a typewriting machine, the combi- 110
nation of a ribbon spool having a circular
track at one end with an opening therein,
a pivoted bridge held in position to close
said opening by the ribbon, and ribbon feed
reversing mechanism including a trip device
which travels on said track and is adapted
to enter said opening when the ribbon is
exhausted from the spool and releases said
bridge, substantially as set forth.
29. In a typewriting machine, the combi- 115
nation of a ribbon spool having a recess in
one end with a surrounding circular track
having an opening therein, a bridge closing
said opening, and ribbon reversing mechan-
ism including a trip device which travels on
said track, and a ribbon coiled around the
track and bridge, substantially as set forth.
30. In a typewriting machine, the combi- 120
nation of a ribbon spool having at one end
a circular track with an opening therein, a
ribbon feed reversing mechanism including
a trip device which travels on said circular
track, a pivoted bridge normally closing the
opening in said track and forming a part 125
of the track, and a ribbon secured to the
bridge for opening it when the ribbon is ex-
hausted from the spool, substantially as set
forth.
31. In a typewriting machine, the combi- 130
nation of a ribbon spool having a circular
wall with an opening, ribbon feed mechan-
ism including a trip device which travels on
said circular wall, a bridge closing the open-
ing in said wall, and a ribbon attached to
said bridge and acting to open the same
when the ribbon is exhausted from the spool
and to close and secure the bridge when
wound upon the spool, substantially as set
forth.
32. In a typewriting machine, the combi- 135
nation of a ribbon spool having a circular
track with an opening therein, a bridge clos-
ing said opening and pivoted at one end and
having an extension at the other end over-
lapping said track, a ribbon secured to said
bridge for opening and closing the same, and
ribbon feed reversing mechanism including
a trip device which travels on said track
and is adapted to enter said opening, sub-
stantially as set forth.
33. In a typewriting machine, the combi- 140
nation of a ribbon spool having a circular

track with an opening therein, a bridge closing said opening and pivoted at one end to the spool, said bridge having inner and outer ribbon holding parts, and ribbon feed reversing mechanism including a trip device which travels on said track and is adapted to enter said opening, substantially as set forth.

34. In a typewriting machine, a ribbon spool having a circular track at each end adapted to surround and coöperate with a ribbon feed reversing trip, and a supporting spool shaft on which the spool is reversible, substantially as set forth.

35. In a typewriting machine, the combination of ribbon spools arranged at opposite sides of the machine, means for feeding the ribbon from one spool to the other, a rotatable reversing shaft extending transversely of the machine at the upper front part thereof with its end portions adjacent to said spools, and means operated by turning said shaft for reversing the ribbon feed, substantially as set forth.

36. In a typewriting machine, the combination of ribbon spools supported at the upper front part of the machine, means for feeding the ribbon from one spool to the other, a reversing shaft having an intermittent rotary motion extending across the front upper part of the machine, and means operated by said shaft for reversing the ribbon feed with each forward movement of said shaft, substantially as set forth.

37. In a typewriting machine, the combination of ribbon spools supported at the upper front part of the machine, means for feeding the ribbon from one spool to the other, a reversing shaft having an intermittent rotary motion extending across the front upper part of the machine, and means operated by said shaft for alternately changing the direction of the ribbon feed, substantially as set forth.

38. In a typewriting machine, the combination of ribbon spools arranged at opposite sides of the front part of the machine, means for feeding the ribbon on the spools, a rotatable shaft extending transversely of the machine with its opposite ends adjacent to said spools, and means operated by said shaft for disconnecting the feeding means from one spool and simultaneously restoring the feeding means to the other spool, substantially as set forth.

39. In a typewriting machine, the combination of a pair of ribbon spools, means for driving the spools to feed the ribbon, a power-driven rotatable shaft arranged with a portion thereof in the vicinity of each of said spools, and means operated by the rotation of said shaft for reversing the feed of the ribbon, substantially as set forth.

40. In a typewriting machine, the combination of ribbon spools supported at the up-

per front part of the machine, means for feeding the ribbon onto the spools, a power-driven shaft extending across the machine, and means operated by the rotation of the shaft for reversing the feed of the ribbon, substantially as set forth.

41. In a typewriting machine, the combination of ribbon spools, means for feeding the ribbon on the spools, a power-driven rotatable shaft, means operated by the rotation of said shaft for reversing the feed of the ribbon, and trip means controlled by the ribbon and acting to automatically release said shaft and permit it to act when the ribbon is exhausted from one spool, substantially as set forth.

42. In a typewriting machine, the combination of ribbon spools, a power-driven shaft, means operated by the rotation of the shaft in one direction for reversing the feed of the ribbon, the rotation of said shaft in the opposite direction acting to store power in its power driving means, and means controlled by the ribbon and acting to automatically release the shaft and permit it to act when the ribbon is exhausted from one spool, substantially as set forth.

43. In a typewriting machine, the combination of a pair of ribbon spools, means for feeding the ribbon on the spools, power-driven mechanism which derives its power independently of the carriage driving motor and of the ribbon for reversing the ribbon feeding means, and means controlled by the ribbon for automatically releasing said power-driven reversing mechanism, substantially as set forth.

44. In a typewriting machine, the combination of ribbon spools, means for feeding the ribbon on the spools, spring-driven mechanism independent of the carriage driving motor for reversing the ribbon feed, means controlled by the ribbon for automatically releasing said reversing mechanism, and means for manually winding said spring, substantially as set forth.

45. In a typewriting machine, the combination of ribbon spools, means for feeding the ribbon on the spools, a spring-driven mechanism acting by the power of the spring when once wound to reverse the ribbon feed a plurality of times, and controlling means for automatically releasing said spring mechanism to reverse the ribbon feed whenever the ribbon is exhausted from one of the spools, substantially as set forth.

46. In a typewriting machine, the combination of ribbon spools, a carriage driving motor and connections for feeding the ribbon on the spools, and a spring-driven mechanism which derives its power independently of the carriage driving motor and of the ribbon for automatically reversing the ribbon feed whenever the ribbon is ex-

hausted from one of the spools, substantially as set forth.

47. In a typewriting machine, the combination of a pair of ribbon spools, a plurality of ribbons wound together face to face on said spools, guides for holding said ribbons from contact adjacent to the spools, and separate guides for said ribbons adjacent to the platen, substantially as set forth.

10 48. In a typewriting machine, the combination of a pair of ribbon spools, a plurality of ribbons wound together face to face on the spools, and a guide for the ribbons near each spool having a separate guide slot for 15 each ribbon, substantially as set forth.

49. In a typewriting machine, the combination of a pair of ribbon spools, a pair of ribbons wound on the spools, a vibrating carrier, a pair of guides adjustably mounted 20 on the carrier to hold one ribbon laterally in advance of the other with relation to the printing point, and a movable part acting by successive like movements to change the relation of the ribbons regardless of which 25 one may be in advance, substantially as set forth.

50. In a typewriting machine, the combination of a pair of ribbon spools, a pair of ribbons wound on said spools, a vibrating 30 carrier, a pair of ribbon guides supported by the carrier, and means for shifting said guides to place either ribbon in position to be vibrated to and from the printing point, and one of the guides having provision for placing either of two portions of its ribbon in 35 position to be vibrated to and from the printing point, substantially as set forth.

51. In a typewriting machine, the combination of a ribbon, a vibrating carrier, a 40 ribbon guide mounted on the carrier, a rocker centrally pivoted to the carrier and connected with the guide, and a manually movable part for shifting said rocker to alternately raise and lower the guide on the 45 carrier, substantially as set forth.

52. In a typewriting machine, the combination of a ribbon, a vibrating carrier, a ribbon guide having a projecting pin supported by the carrier, a pivoted rocker having a slot receiving said projecting pin, and means for rocking said rocker on its pivot, substantially as set forth.

53. In a typewriting machine, the combination of a pair of ribbons, a pair of ribbon 55 guides, a vibrating carrier for said guides, a rocker pivoted on said carrier and connected to said guides, and means for rocking said rocker to shift said guides on the carrier, substantially as set forth.

60 54. In a typewriting machine, the combination of a pair of ribbons, a pair of ribbon guides, a vibrating carrier for said guides, a rocker pivoted on said carrier and connected to said guides and having oppositely

inclined edges, and a pivoted lever and 65 operating means for alternately engaging said inclined edges of said rocker to rock it in opposite directions, substantially as set forth.

55. In a typewriting machine, the combination of a pair of ribbons, a pair of ribbon guides, a vibrating carrier for said guides, a rocker pivoted on said carrier and connected to said guides and having oppositely 70 inclined edges, a lever pivoted to swing horizontally to engage either of said inclined edges and vertically to rock said rocker, means for swinging said lever vertically, and means for normally holding said lever centrally relative to said inclined edges, 75 substantially as set forth.

56. In a typewriting machine, the combination of a ribbon, a ribbon guide, a carrier on which said guide is adjustably mounted, and two parallel links pivotally connected to 80 the carrier at their front ends and to the machine at their rear ends for movably supporting the carrier in upright position, and means for vibrating said links to raise and lower said carrier, substantially as set forth. 85

57. In a typewriting machine, the combination of a ribbon, a carriage, a shift frame for the carriage, a vibrating ribbon carrier, supporting links for said carrier pivotally connected to said shift frame and to said 90 carrier, and means for vibrating said links substantially the same distance with the shift frame in either of its positions, substantially as set forth.

58. In a typewriting machine, the combination of a ribbon, a carriage, a shift frame for the carriage, a ribbon guide, a carrier on which the guide is adjustably mounted, links pivotally connected to the shift frame and to the 100 carrier, and means for vibrating said links substantially the same distance with the shift frame in either of its positions, substantially as set forth.

59. In a typewriting machine, the combination of a carriage, a carriage shift frame, 105 a ribbon, a ribbon guide, a carrier for said ribbon guide, links pivotally supporting said carrier from said shift frame, means connected to one of said links for vibrating said carrier in different positions of the shift frame, a lever pivoted to said shift frame for shifting said ribbon guide on said carrier, and means connected to said lever for operating it in different positions of the shift frame, substantially as set forth. 110

60. In a typewriting machine, the combination of a pair of ribbon spools, a pair of ribbons wound on said spools, and an equalizing device for taking up the slack in either of the ribbons, substantially as set forth. 115

61. In a typewriting machine, the combination of a pair of ribbon spools, a pair of ribbons wound on the spools, and a spring-

actuated device for equalizing the tension of the ribbons, substantially as set forth.

62. In a typewriting machine, the combination of a pair of ribbons, means for feeding said ribbons together lengthwise, and a device for equalizing the tension of said ribbons consisting of a part arranged between said ribbons, and means for causing said

part to bear yieldingly against either ribbon, substantially as set forth.

Witness my hand, this 27th day of April, 1907.
